UNITED STATES PATENT OFFICE.

FRANCIS M. WILDER AND GEORGE H. BENJAMIN, OF NEW YORK, N. Y.

FLEXIBLE PIPING.

SPECIFICATION forming part of Letters Patent No. 376,401, dated January 10, 1888.

Application filed July 19, 1887. Serial No. 244,712. (No model.)

To all whom it may concern:

Be it known that we, FRANCIS MILTON WILDER and GEORGE H. BENJAMIN, of the city, county, and State of New York, have invented certain new and useful Improvements 5 in Flexible Piping, of which the following is a specification.

Our invention relates to flexible piping, such as is designed to carry steam or other heated fluids or gases, and what will not be readily acted upon by the fluid or gases, and at the same time present a certain degree of mobility or flexibility when in use.

Our invention has special reference to hose 15 or piping adapted to be employed between railway-cars for transmitting steam or other heated gases.

In the accompanying drawings, which illustrate our invention, similar letters of reference 20 indicate like parts.

Figure 1 is an elevation of the main body of the piping and the various coverings superposed thereon. Fig. 2 is a longitudinal vertical section. Fig. 3 is a transverse section taken 25 on the line X X of Fig. 2. Fig. 4 is a transverse section taken on the line Y Y of Fig. 2.

In the drawings, A indicates the main body of the piping, made up of independent sections of spun or cast metal or other suitable material. Each section is so made that one end, B, 30 is slightly smaller than the opposite end, C, whereby the end B of one section will fit into the end C of the next section.

The sectional view, Fig. 2, shows the sections 35 A to have their surface formed convex at the ends and concave in the center. By so arranging the sections considerable mobility may be obtained between the independent sections without separating them or allowing the egress 40 of the body transmitted.

We do not wish to limit ourselves to the exact shape of the sections as shown, as the ball-and-socket effect may be obtained in very many different ways; neither do we wish to limit our-

5 selves to the use of metal as the material from which to form the body of the piping. Very many materials may be employed—such as paper or glass—without departing from the intent of our invention.

Arranged over the body of the piping is a 50 layer of asbestos or similar material, D—such, for instance, as mineral wool. Any material which is not combustible will answer the required purpose, the object of which is to form a packing-covering which will serve to lag the 55 piping. Over this lagging D is indicated a layer of india-rubber or other material impervious to the passage of steam or gases. Vulcanite, okonite, vulcanized fiber, or like materials will answer a similar purpose. The external surface of the pipe we prefer to envelop 60 with a covering of woven cotton, F, such a covering as is usually employed for covering hose-pipe, and which, when properly applied, will stand a very high internal bursting pressure. 65

We are aware that a hose made of a number of independent sections articulating with each other and contained within a covering or containing-tube has heretofore been made, and such we do not broadly claim.

We claim as our invention—

1. The combination, in a flexible piping, of the articulating section A, the non-combustible covering D, the impervious covering E, and the outer covering, F.

2. The combination, in a flexible piping, of the sections A, the ends of which, C B, are of different diameters, the non-combustible covering D, the impervious covering E, and the outer covering, F, all substantially as described. 80

In witness whereof we have hereunto set our hands the 18th day of July, 1887.

F. M. WILDER.
GEO. H. BENJAMIN.
